United States Patent Office.

SPENCER H. BROWN AND CHARLES H. WILLETS, OF NEW YORK, N. Y.

Design No. 3,081, dated June 30, 1868.

DESIGN FOR A TOY-GUN.

The Schedule referred to in these Letters Patent and making part of the same.

TO ALL WHOM IT MAY CONCERN:

Be it known that we, SPENCER H. BROWN and CHARLES H. WILLETS, both of New York, in the county and State of New York, have invented a new and ornamental Design for Toy-Gun; and we do hereby declare the following to be a full, clear, and exact description thereof, which will enable those skilled in the art to make and use the same, reference being had to the accompanying drawing.

The drawing represents a top view of this design.

This design relates to a toy-gun, the breech of which is ornamented with a flower, *a*, the leaves of which terminate close under a bead, *b*. At a certain distance from the bead *b* are two more beads, *c d*, separated from each other by a string of pearls, *e*. A similar pair of beads, *f g*, with an intermediate string of pearls, *h*, ornaments the central portion of the barrel, and the front part of the barrel is fluted, as shown.

Having thus described our invention, what we claim as new, and desire to secure by Letters Patent, is—
The design for a toy-gun, as shown and described.

SPENCER H. BROWN,
CHAS. H. WILLETS.
